SHOWER CABINET

Carl E. T. Johnson, Jamestown, N. Y., assignor to
 Jamestown Steel Partitions, Inc., Jamestown,
 N. Y., a corporation of New York

Application June 19, 1940, Serial No. 341,367

15 Claims. (Cl. 189—2)

This invention relates to shower cabinets and more particularly to an improved shower cabinet formed from a few separable and interchangeable parts and sections which can be shipped to the place of use in knockdown condition and assembled at the place of use by unskilled labor and with a minimum of effort.

In accordance with this invention, an improved metal shower cabinet is presented, which can be made from sheet metal, which is sturdy and strong in construction, highly attractive in design and appearance, and which can be made with a minimum of operations and at minimum cost.

Another object of this invention is to provide an improved shower cabinet so constructed that it may be assembled at the plant from a minimum number of parts and which may be interchangeably assembled in the field by unskilled labor to suit field conditions without special fittings or screws.

Still another object of this invention is to provide an improved shower cabinet formed into sections or units at the plant from a minimum number of parts, which sections or units may be interchangeably assembled, telescoped and snapped together in the field.

Other objects of this invention will become apparent as the disclosure proceeds.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a perspective view of the shower cabinet;

Fig. 2 is a cross-sectional view of the cabinet as it appears when looking in the direction of the arrows 2—2 of Fig. 1;

Fig. 3 is a cross-sectional view of the cabinet as it appears when looking in the direction of the arrows 3—3 of Fig. 1;

Fig. 4 is a horizontal cross-sectional view of the cabinet as it appears when looking in the direction of the arrows 4—4 of Fig. 3, certain parts being broken away to illustrate certain structural details; and

Fig. 5 is a fragmentary perspective view of a portion of the base and side wall panels, certain parts being broken away to illustrate certain structural details.

Similar reference characters refer to similar parts throughout the several views of the drawings and the specification.

Referring to the drawings, this shower cabinet comprises a base unit 1, interchangeable side wall sections 2 and 3, a rear wall section 4, a top frame member 5 and a curtain hanger 6, which are rigidly assembled at the plant as individual units ready for quick erection in the field.

The base unit 1 is formed from only three main pieces of sheet metal formed to provide a pan member 10 supported upon a base frame 20 and an intermediate frame 26. The base frame 20 is formed from a single elongated strip of sheet metal of suitable gauge which is bent into generally channel-shaped form, as shown in Figs. 2, 3 and 5. This channel-shaped sheet metal strip comprises essentially a side wall forming portion 21 which constitutes the bottom of the channel, an inturned flange 22 which is to rest on the floor of the building in which the cabinet is installed, and an inturned flange 23 upon which the pan 10 seats. The flange portion 22 may be provided with an upturned lip 24 to stiffen and strengthen the base frame. After the channel section 20 has been formed, it is bent to provide a rectangular frame by cutting V-shaped notches in the flanges 22 and 23 of the channel at the corners of the frame to provide a mitered joint secured by welding. The meeting ends of the channel-shaped section when bent into rectangular form are also welded together to provide a sturdy and rigid frame.

The pan member 10 is also formed from a single piece of sheet metal comprising a sloping bottom wall 30 which is defined by four sloped triangular shaped bottom wall portions 37 defined by radiating crease lines 40 which radiate from a central drain aperture 38. The inner ends of the triangular shaped portions 37 may be depressed so as to present a generally depressed circular flange 39 to provide a seat for a suitable drain cover. The periphery of the bottom wall terminates in upturned vertical wall portions which form the front wall 11, side walls 12 and 14, and rear wall 13 of the base unit. The free ends of these vertical walls are suitably welded together at the corners. The inturned flange 23 of the base frame 20 is secured as by spot welding 36 to the bottom wall 30 of the pan adjacent the periphery thereof. The side wall forming

portion 21 of the base frame 20 is arranged, so that its outside surface is substantially in alignment with the outside surface of the adjacent front wall 11, side walls 12 and 14, and rear wall 13 of the base unit.

The bottom wall 30 of the pan member is reinforced by a rectangular shaped frame 26 which surrounds the opening 38 and which is positioned within the base frame 20. The intermediate reinforcing frame 26 is formed from a single strip of sheet metal which is first bent into a Z-shaped cross-sectional contour, providing a vertical leg portion 27, an outturned flange portion 28 and an inturned flange portion 29. The Z member is bent into rectangular shape by cutting slits in the outturned flange 28 and by cutting V notches in the inturned flange 29, the adjacent edges of the V cuts being secured together as by welding. The ends of the leg portion 27 of the Z frame when bent into rectangular form are secured together as by welding. The outturned flange 28 of the frame 26 is secured to the bottom wall 30 of the pan member as by spot welds 28'. The frame 26 is so shaped that the inturned flange 29 thereof will rest upon the floor upon which the cabinet is supported.

The side wall sections 2 and 3 are each formed from a single piece of sheet metal and when formed are identical in shape. Each of the side wall sections 2 and 3 comprises a side wall panel 31 and an inturned panel portion 32 at each end thereof. Each inturned panel portion 32 has its free edge shaped into tube formation 32' comprising an edge portion 33 bent at right angles to panel portion 32, a rebent portion 34 extending generally parallel to the panel portion 32, and an inturned lip portion 35 extending inwardly toward the adjacent panel portion 32. Each side wall section is thus provided with two panel portions 32 having their free side edges bent into tube formation 32' so that either panel portion 32 may be positioned to form a part of the rear wall of the cabinet or part of the front wall of the cabinet.

One of the side wall sections 2 is provided with a pair of spaced apertures 90 through which hot and cold water control fixtures 91 extend. It will be appreciated that the water control fixtures 91 are suitably connected to hot and cold water piping outside of the side wall section 2 of the cabinet. Side wall section 2 is also provided with an opening 92 adjacent the top thereof through which a portion of the spray head fixture 93 extends, which is also connected to the water supply pipe. It will be appreciated that since the side wall sections 2 and 3 are identical in form, the side wall section 2 carrying the water fixture openings may be positioned on either the right hand side or left hand side of the cabinet, to suit field conditions.

The rear wall section 4 comprises a relatively flat rear panel 41 which is the same height as the side wall sections 2 and 3 and which is of a width sufficient to fit snugly between the inturned side portions 33 of the adjacent side wall sections. Each side edge of the rear wall panel 41 is provided with an inturned portion 42 designed to snugly overlie the side portion 33 of the adjacent side wall section, an outturned portion 43 designed to snugly overlie the edge portion 34 of the side wall section, and a rebent lip portion 44 which extends at an acute angle with respect to portion 43 so as to frictionally grip the inturned lip portion 35 of the adjacent side wall section. It will be appreciated that by bending the lip

portion 44 at an acute angle with respect to the portion 43, this lip portion resiliently grips the adjacent lip portion 35 of the side wall section so as to frictionally but rigidly retain the rear panel section 4 in fixed upright position. In the construction here provided no screws or other securing means are needed to secure the rear wall section 4 to the adjacent side wall sections 2 and 3. A saving in material and substantially greater speed of erection and demolition are thus realized.

The rear wall section 4 and each of the side wall sections 2 and 3 are provided with spaced angle-shaped clips 56 at the lower end thereof, which are secured thereto at spaced intervals. Each of these clips comprises a relatively flat leg portion 57 secured to the adjacent side wall or rear wall section as by spot welds 58, an offset portion 59, a downturned leg portion 60, and an outwardly flared lip portion 61. Each of the vertical walls 11, 12, 13 and 14 of the base unit carries an angle-shaped bar 50 on the inside face thereof with which the clips 56 are arranged to interlock to detachably secure the side and rear wall sections in rigid vertically extending position. Each angle-shaped bar 50 comprises a downturned leg 51 which is secured to the adjacent vertical wall of the base unit as by spot welds 52, an inturned hip portion 53, and an upturned leg portion 54 which is so shaped as to snugly seat against the outside face of the adjacent side or rear wall section. The upwardly extending leg 54 seats within a pocket 55 defined between the downturned leg portion 60 of the clip 56 and the adjacent outside face of the side or rear wall section. The clips 56 are formed from sheet metal, generally referred to as Z-bar in form, and may be of almost any length from one inch to substantially the width of the side and rear wall section across which it extends. While the bar 50 preferably extends along substantially the entire vertical wall of the pan, it also may be cut into spaced sections, if desired.

When erected, the lower edges of the side wall sections 2 and 3 and rear wall section 4 are designed to seat snugly against the inside face of the bottom wall 30 of the pan 10 and are held in spaced relationship from the adjacent vertical walls 11, 12, 13 and 14 of the base unit, which vertical walls are each provided with a generally rounded inturned flange portion 15 which has a free edge 16 which abuts the outside face of the adjacent side or rear wall section. Thus the side wall sections 2 and 3 and the rear wall section 4 are rigidly braced and held in fixed erect position by the bracing action of the edges 16 as well as by the bars 50 interlocking with the clips 56. The inturned flange portion 15 forms with the adjacent vertical walls 11, 12, 13 and 14 and the adjacent side and rear wall sections an enclosed housing 62 within which the locking bars 50 and the locking clips 56 are housed and contained. The rounded flange portion 15 of the vertical walls 11, 12, 13 and 14 of the base unit gives the cabinet an attractive and decorative contour which measurably adds to its finished appearance.

The front wall 11 of the base unit, as shown more particularly in Figs. 1, 2 and 3, is provided with an inturned tread portion 18 which is formed integral therewith and which extends between the inturned side portions 33 which define the entrance opening into the cabinet. The tread portion 18 extends a convenient distance

inwardly so as to provide a smooth and comfortable foot tread. The ends 18' of the tread portion 18 are so cut and formed as to snugly abut the inturned edge portions 33 of the adjacent side wall sections so as to firmly brace the side wall sections at the lower end thereof against inward movement. The tread portion 18 is provided with a downturned flange portion 19 which terminates in an outturned lip portion 19', which further strengthens and stiffens the tread portion and gives the interior of the cabinet a finished appearance, free from raw edges which might otherwise cause injury to the occupant.

The top edges of the side wall sections 2 and 3 and rear wall section 4 are enclosed within a rectangular shaped head frame 5 which is formed from a single piece of sheet metal of a generally channel shape in cross-section. The sheet metal strip from which the head frame 5 is formed is first bent into the cross-section generally illustrated in Figs. 1 and 3 comprising generally a downturned leg portion 10, a top flange portion 11 bent at right angles to the leg portion 10, and a rounded embracing flange portion 12. The flange portion 11 and the rounded flange portion 12 are provided with V notches which permit the shaped strip to be bent into rectangular form, the free edges adjacent the notches being secured together as by welding. The free ends of the leg portion 10 of the strip are also secured together by welding so as to provide a rigid rectangular-shaped head frame. It will be noted by referring more particularly to Fig. 3 that the inner edge 13 of the rounded flange portion 12 of the head frame is arranged to abut against adjacent faces of the side and rear wall sections, so that these sections are held in rigid rectangular alignment. The leg portion 10 is also so arranged as to generally align with the vertical walls 11, 12, 13 and 14 of the base unit positioned therebelow so as to produce a symmetrical arrangement of the parts, free from protruding raw edges, providing a framed appearance for the lower and upper ends of the cabinet having a rounded and attractive symmetry.

To prevent movement of the upper end of the side wall sections within the head frame 5, the flange portion 11 preferably terminates in a downturned lip 14 which is so spaced as to snugly engage the inside face of the portions 43 of the rear wall section 4 and the portions 34 of the side wall sections adjacent the entrance way to the cabinet. The downturned lip portion 14, formed as an integral part of the head frame 5, rigidifies the head frame construction and provides means to prevent in-bowing of the side and rear wall sections. If further means are desired to hold the frame in position, paired tongue portions 75 may be struck out from the inturned flange portion 11 of the head frame. The paired downwardly extending tongues 75 are so positioned and arranged as to snugly fit within the interior of the tube formations 32' formed at the free edges of the panel portions 32 of each side wall section. The downwardly extending paired tongues 75 provide abutments which further prevent inward movement of the side wall sections 2 and 3 and provide means for frictionally retaining the head frame 5 in its telescoped position over the side wall sections and the rear wall section of the cabinet. As further or alternate securing means, tongues 76 may be struck out from the inturned flange portion 11 at spaced intervals so as to abut against the inside face of the wall forming panels 31 of the side wall sec-

tions 2 and 3, the wall forming panel 41 of the rear wall section and the wall forming panel 32 of the side wall sections.

It will be appreciated that under normal conditions the downturned lip portion 14 may be amply sufficient to hold the upper end of the side and rear wall sections in rigid rectangular alignment, but if this is not sufficient the paired tongues 75 or the single tongues 76 or both may be used in conjunction therewith. If the downturned lip 14 is not used either the paired tongues 75 or the single tongues 76 or both may be selectively used as desired.

A curtain rod 6, which may be a solid rod or bar or a hollow tube, is supported by suitable brackets 78 secured to the head frame. Each bracket 78 may be formed from a stamped piece of sheet metal comprising an outturned base portion 79 secured as by spot welds to the inturned top flange portion 11 of the head frame in a position to support the curtain rod 6 and the curtain depending therefrom in convenient position adjacent the entrance way into the cabinet. A leg portion 80 extends downwardly from the base portion 79 and, as shown more particularly in Fig. 2, is provided with a bayonet slot 81 which terminates in a depressed circular seat 82 within which the end of the rod 6 may rest. The curtain rod 6 is of such length as to extend between the side wall panels 31 of the side wall sections and may be quickly placed in supported position upon the paired brackets 78 when the cabinet has been erected.

It will be appreciated that a shower cabinet 35 constructed in accordance with this invention may be quickly formed and assembled at the plant from relatively few parts formed into a few separate units or sections. The base pan 10 is formed from a single sheet of metal which can 40 be quickly stamped and bent into the desired shape to form not only the bottom wall 30 of the base unit but the vertical walls 11, 12, 13 and 14. The vertical walls where they extend adjacent the side wall sections and the rear wall section 45 of the cabinet are provided with a rounded inturned flange portion 15 formed by a simple stamping operation. The front wall 11 adjacent the entrance way is provided with a tread portion 18 integral therewith, shaped by a simple 50 stamping operation. Heretofore the threshold tread has been formed as a separate piece of complicated construction and difficult to attach. The base frame 20 and the intermediate frame 26 are each shaped from a single strip of sheet 55 metal and quickly secured as by spot welds to the bottom wall 30 of the pan. The locking bars 50 extending around the inside face of the vertical walls 11, 12, 13 and 14 of the pan may also be quickly secured to these vertical walls by spot 60 welds, completing the assembly of the base unit.

The side wall sections 2 and 3 are identical in shape and may be kept in stock. Either one of these sections may be provided with apertures 90 and 92 to receive the piping fixtures, and they 65 are so shaped as to permit interchangeable assembly in the field. The side wall sections 2 and 3 and the rear wall section 4 are each provided with a series of spaced clips 56 secured thereto as by spot welding and arranged to telescope over and securely interlock with the adjacent locking bars 50. The rear wall section 4 of the cabinet may be quickly snapped into position 70 between the adjacent panel portions 32 of the erected side wall sections 2 and 3. The head 75 frame 5 is applied by telescoping the same over

the side and rear wall sections with the tongues 75 inserted in the tube formations 32' of the side wall sections so as to fixedly secure the head frame in position and prevent inward movement of the side wall sections. The curtain rod hanger 6 is then placed in position, completing erection of the cabinet. Plumbing connection to the water piping and drain outlet can be conveniently made due to the interchangeability of the side wall sections 2 and 3.

It will be noted that the improved cabinet herein disclosed can be quickly assembled and erected in the field without the application of screws, fitting of the parts or other time-consuming erection operations. The cabinet can be quickly dismantled for storage or erection at another location, as desired. This improved cabinet assembly combines low cost in manufacture and erection, interchangeability of the parts to accommodate varied field conditions, sturdiness of construction, and a highly attractive and symmetrical appearance.

While certain novel features of the invention have been disclosed and are pointed out in the annexed claims, it will be understood that various omissions, substitutions and changes may be made by those skilled in the art without departing from the spirit of the invention.

What is claimed is:

1. A shower cabinet comprising, a receptor unit, a pair of side wall sections and a rear wall section supported by the receptor unit, said side wall sections having duplicate front and rear panel portions terminating in vertical tubular formations, said rear wall section having U-shaped formations along its vertical edges overlapping the adjacent tubular formations of said side wall sections, said U-shaped formations having resilient lips frictionally gripping said tubular formations retaining said side and rear wall sections in rigid erect assembled position.

2. A shower cabinet comprising, a receptor unit, a pair of side wall sections and a rear wall section supported by the receptor unit, said side wall sections having duplicate front and rear panel portions terminating in vertical tubular formations, one of said side wall sections having a shower device receiving opening therein, said side wall sections being interchangeable from side to side of the receptor unit to adapt the shower cabinet for receiving water supplied from either side, said rear wall section having U-shaped formations along its vertical edges overlapping the adjacent tubular formations of said side wall sections, said U-shaped formations having resilient lips frictionally gripping said tubular formations retaining said side and rear wall sections in rigid erect assembled position.

3. A shower cabinet comprising, a receptor unit including a base member and a one-piece metal pan member supported on said base member, said pan member comprising a bottom wall and vertically extending enclosing walls integrally formed with said bottom wall, a pair of side wall sections and a rear wall section extending into the pan of the receptor unit, said side wall sections having duplicate front and rear panel portions, one of said side wall sections having a shower device receiving opening therein, said side wall sections being interchangeable from side to side of the receptor unit to adapt the shower cabinet for receiving water supplied from either side, and cooperating means for detachably securing said side and rear wall sections in rigid erect position to the adjacent

vertical walls of the pan, said means including inturned flange portions integrally formed with the vertical walls of the pan abutting and embracing said sections at a point substantially above the lower ends thereof, and cooperating interlocking bars secured to said sections and said vertical pan walls below said inturned flange portions and normally concealed therebetween.

4. A shower cabinet comprising, a receptor unit, a pair of side wall sections and a rear wall section supported by the receptor unit, said side wall sections having duplicate front and rear panel portions, one of said side wall sections having a shower device receiving opening therein, said side wall sections being interchangeable from side to side of the receptor unit to adapt the shower cabinet for receiving water supplied from either side, a head frame seating over the top ends of said side and rear wall sections, said head frame having a downturned flange portion extending interiorly over the upper ends of said side and rear wall sections and lugs struck out from said head frame frictionally engaging said side wall sections for detachably securing the head frame thereto.

5. A shower cabinet comprising, a receptor unit, a pair of side wall sections and a rear wall section supported by the receptor unit, said side wall sections having duplicate front and rear panel portions terminating in tubular formations, a head frame seating over the top ends of said side and rear wall sections, and means projecting from said head frame into said tubular formations for detachably securing the head frame to the side wall section.

6. A shower cabinet comprising, a receptor unit comprising a base frame and a pan member supported thereon, said pan member having a bottom wall and vertically extending side walls integrally formed with said bottom wall, a pair of side wall sections and a rear wall section extending into and substantially abutting the bottom wall of said pan member, said side wall sections having duplicate front and rear panel portions, said rear wall section extending between said rear panel portions, said front panel portions being conveniently spaced to provide an entrance way therebetween, and means associated with said side and rear wall sections for detachably securing said sections in rigid erect position to the adjacent vertical walls of the pan, said means including inturned flange portions integrally formed with the vertical walls of the pan abutting and embracing said sections at a point substantially above the lower ends thereof, and cooperating interlocking bars secured to said sections and said vertical pan walls below said inturned flange portions and normally concealed therebetween, one of said vertical walls having an integral tread portion extending inwardly between said front panel portions providing a threshold for the entrance way, the ends of said tread portion substantially abutting the adjacent vertical edges of said front panel portions.

7. In shower cabinet construction, a receptor unit comprising a rectangular-shaped sheet metal base member of generally channel-shaped cross-section and a sheet metal shower pan having a bottom wall and four upstanding vertical walls extending continuously around the bottom wall resting upon and secured to an inturned flange of said base member, a pair of side wall sections and a rear wall section having the lower ends thereof extending into said pan and sup-

ported by the bottom wall thereof, three of the vertical walls of said shower pan having inturned flange portions abutting against the adjacent sections and the fourth wall having an inturned tread portion integrally formed therewith extending between said side wall sections to provide an entrance way threshold and means normally concealed between the vertical walls of the pan and the adjacent side and rear wall sections for detachably securing said sections to the vertical walls of the pan, the ends of said tread portion substantially abutting the adjacent vertical edges of said side wall sections.

8. In shower cabinet construction, a receptor unit comprising a rectangular-shaped sheet metal base member of generally channel-shaped cross-section presenting a vertically extending supporting wall and a pair of inturned spaced flanges, and a shower pan having a bottom wall and connected vertical walls, means for permanently securing one of said flanges to the bottom wall of the pan, the vertical walls of the pan having rounded inturned flange portions, a pair of side wall sections and a rear wall section having the lower ends thereof extending into and substantially abutting the bottom wall of the pan with the inturned flanged portions substantially abutting the adjacent outside faces of the adjacent side and rear wall sections, and means normally wholly concealed between the vertical walls of the pan and the adjacent side and rear wall sections for detachably securing said sections to the vertical walls of the pan.

9. In shower cabinet construction, a receptor unit comprising a rectangular-shaped sheet metal base member of generally channel-shaped cross-section presenting substantially vertically extending supporting walls and upper and lower inturned flanges, and a shower pan having a bottom wall and vertically extending enclosing walls supported upon and secured to said upper inturned flanges, a pair of side wall sections and a rear wall section having the lower ends thereof extending into and substantially abutting the bottom wall of the pan, the vertical walls of the pan having inturned flange portions whose free edges abut the outside faces of said sections, and cooperating means fixed to and normally concealed between said vertical walls and said sections for detachably interlocking said sections to the adjacent vertical walls of the pan.

10. In shower cabinet construction, a receptor unit comprising a rectangular-shaped sheet metal base member having substantially vertically extending enclosing walls and spaced upper and lower inturned flanges, and a shower pan having a bottom wall and vertically extending sheet metal enclosing walls fixed to the upper inturned flanges of said base member, a pair of side wall sections and a rear wall section having the lower ends thereof extending into and substantially abutting the bottom wall of the pan, and means associated with said side and rear sections for detachably securing said sections in rigid erect position to the adjacent vertical walls of the pan, said means including inturned flange portions integrally formed with the enclosing walls of the pan abutting and bracing said sections at a point substantially above the lower ends thereof, and cooperating interlocking elements secured to said sections and vertical walls below said inturned flange portions.

11. In shower cabinet construction, a receptor unit comprising a rectangular-shaped sheet metal base member having substantially vertical-

ly extending supporting walls, and a shower pan having a bottom wall and vertically extending enclosing walls formed integrally with said bottom wall, said pan being supported upon and secured to said base member, a pair of side wall sections and a rear wall section extending into the pan, said side wall sections having duplicate front and rear panel portions, said rear wall section extending between said rear panel portions, said front panel portions defining an entrance way therebetween, and means associated with said side and rear wall sections for detachably securing said sections in rigid erect position to the adjacent vertical walls of the pan, said means including inturned flange portions integrally formed with the enclosing walls of the pan abutting and embracing said sections at a point substantially above the lower ends thereof, and cooperating interlocking bars secured to said sections and said vertical pan walls below said inturned flange portions and normally concealed therebetween, one of said vertical walls having an inturned tread portion formed integrally therewith extending inwardly between said front panel portions with the ends of said tread portion substantially abutting the adjacent vertical edges of said front panel portions.

12. In shower cabinet construction, a receptor unit comprising a rectangular-shaped sheet metal base having substantially vertically extending supporting walls and inturned flanges, and a shower pan having a bottom wall and vertically extending enclosing walls, means for permanently securing the inturned flanges of the base to the bottom wall of the pan, a pair of side wall sections and a rear wall section having the lower ends thereof extending into the pan in spaced relation to the vertical walls thereof, and interlocking means positioned between said vertical walls and said sections for detachably securing said sections to the adjacent vertical walls of the pan, said vertical walls having inturned flange portions extending over said securing member concealing said means from exterior view.

13. In shower cabinet construction, a receptor unit, a pair of side wall sections and a rear wall section having the lower ends thereof extending into said receptor unit, interfitting means associated with the adjacent vertical edges of said side and rear wall sections for connecting said sections, means for detachably securing said side and rear wall sections to the receptor unit, a rectangular-shaped frame member of generally channel-shaped cross-section telescoping over the adjacent side and rear wall sections, having an interior flange portion extending inwardly over said rear and side wall sections, and overlapping the upper end of said interfitting means, and an exterior flange portion having a facing portion spaced from the outside faces of the adjacent sections and an inturned lip portion whose free edge abuts the outside faces of the adjacent sections, said interior flange portion being arranged to snugly engage said interfitting means to hold the upper ends of said side and rear wall sections in fixed assembled position.

14. In shower cabinet construction, a receptor unit, a pair of side wall sections and a rear wall section having the lower ends thereof extending into said receptor unit, interfitting means associated with the adjacent vertical edges of said side and rear wall sections for connecting said sections, means for detachably securing said side and rear wall sections to the receptor unit, a

generally rectangular-shaped frame member of generally channel-shaped cross-section telescoping over the adjacent side and rear wall sections, said frame member having an interior flange portion extending inwardly over the upper ends of said side and rear wall sections and overlapping said interfitting means, and an exterior flange portion of generally rounded contour having the free edge thereof substantially abutting the outside faces of the adjacent sections, and means for detachably securing said frame member to said side wall sections.

15. A shower cabinet comprising a receptor unit, a pair of side wall sections and a rear wall section supported by the receptor unit, said side wall sections each having a rear panel portion terminating in a vertical tubular formation, said

rear wall section having U-shaped formations along its vertical edges overlapping the adjacent tubular formations of said side wall sections, said U-shaped formations having resilient lips 5 frictionally gripping said tubular formations, and a generally rectangular-shaped frame member of generally channel-shaped cross section telescoping over the upper ends of the adjacent side and rear wall sections, said frame member having an exterior flange portion overlapping and abutting the outside faces of the adjacent sections and having an interior flange portion extending inwardly and snugly engaging the inside faces of 10 said U-shaped formations to hold the upper ends 15 of said side and rear wall sections in fixed assembled position.

CARL E. T. JOHNSON.
